Primary Examiner — Wendy L Arminio*Assistant Examiner* — Sherry L Jones(57) **CLAIM**

The ornamental design for a cat litter box, as shown and described.

DESCRIPTION

FIG. 1 is a front, right side perspective view of a cat litter box, showing my new design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof;

FIG. 9 is an exploded view of the cat litter box thereof;

FIG. 10 is an enlarged view of the selected portion 10 in FIG. 9; and,

FIG. 11 is an enlarged view of the selected portion 11 in FIG. 9.

The broken lines shown in the drawings depict portions of the cat litter box that form no part of the claimed design.
